(57) **CLAIM**

The ornamental design for a wave-shaped tablet, as shown and described.

DESCRIPTION

FIG. 1 is a perspective view of a wave-shaped tablet according to my new design.

FIG. 2 is a side perspective view of my wave-shaped tablet.

FIG. 3 is a front side view of my wave-shaped tablet.

FIG. 4 is a right side view of my wave-shaped tablet.

FIG. 5 is a left side view of my wave-shaped tablet.

FIG. 6 is a top side view of my wave-shaped tablet; and, FIG. 7 is a front side view of my wave-shaped tablet illustrated in a stacked arrangement.

The broken line showing in FIG. 7 is included for the purpose of illustrating environment and forms no part of the claimed design.

1 Claim, 1 Drawing Sheet
